TO DANIEL MANSON SUTHERLAND, JR., OF MORRISVILLE, PENNSYLVANIA

MOLD FOR FIBER SHEETS

Application filed November 19, 1930. Serial No. 496,618.

This invention relates to molds for fiber sheets and the like, and aims at improving such molds (especially as against the tendency of fiber sheets formed in them to stick to the molds), at lowering the cost of operation, and at improving the product. How these and other advantages can be realized through the invention will appear from the description hereinafter of a selected and preferred embodiment.

In the drawings, Fig. I shows a vertical section through one form of mold conveniently embodying the invention.

Fig. II is a bottom plan view of the mold top.

Fig. III is a fragmentary sectional view, taken through the mold top as indicated by the line and arrows III-III in Fig. II; and,

Fig. IV is a similar view, taken as indicated by the line and arrows IV-IV in Fig. II.

In practice, raw fiber sheets for the manufacture of fiber board and the like are formed from aqueous pulp by draining or squeezing away the water, leaving the fibers interlaced in a porous, moist, frail aggregate that can afterward be consolidated or compacted into a board, usually by heat and pressure. One way of forming such a "raw" fiber sheet is by means of a mold of the general type illustrated in Fig. I, having a shallow, flat cavity into which the pulp is run from hoppers 9, 9 opening into its opposite edges, and whence the water is drained away when its opposite (top and bottom) walls 10 and 11 are brought together. As here shown, the flat mold cavity is horizontal, and its top 10 is vertically movable relative to its bottom 11, which has a multitude of fine ducts 12, for draining off the water, with a perforated or foraminous screen 13 over them.

The edge walls or deckle 14, including the hoppers 9, 9, are also vertically movable, so that they can be raised away from the bottom 11 to permit removal of the formed sheet. A conveyor of travelling wires or wire screen 15 is shown extending across the bottom 11, beneath the edge walls or deckle 14 of the mold, as a means of conveying the formed sheet away.

In the operation of a wet machine of this character, the mold is initially as shown in Fig. I, when fiber pulp from the hoppers 9, 9 is run into the mold (which is suitably vented of air), filling the mold completely. The mold top 10 is then allowed or caused to descend, and the water of the pulp is thereby squeezed, strained, and drained off through screen 13 and ducts 12, leaving the fibers behind interlaced and matted together in the form of a moist, raw sheet. When the top 10 has descended as far as its weight (or desirable additional pressure) will carry it, the deckle 14 is raised flush with the bottom surface of the mold top 10, or slightly higher, and the top 10 and deckle 14 are then further raised together, so that the formed fiber sheet may be carried away by the conveyor 15. Thereafter, the top 10 and deckle 14 are lowered again to their positions of Fig. I, and the cycle of operations is repeated.

Now in practice, the raw fiber sheet formed in the mold tends to stick to the usual plain, flat lower surface of the metal plate forming the mold top 10 when the latter is raised, only breaking away and falling back on the conveyor wires 15 after "hanging" awhile,—or even requiring to be manually loosened or "started". This not only occasions delay, but also sometimes results in broken or damaged sheets.

In accordance with the present invention, such difficulties are obviated by a different sort of top mold lower surface: i. e., one of porous or elastic character, and preferably both. Elastic vulcanized rubber is a suitable elastic material, and can be had in sheets of sponge rubber that is quite porous,—such as are used to make backing pads for rubber stamps.

Fig. I shows the mold top 10 provided with a bottom facing pad 16 of sponge rubber, secured in any suitable way,—as by cementing it to a metal backing plate 17 forming part of the mold top, and detachably secured by screws 18. Preferably, the backing plate 17 has its margins and corners augmented on a concave bevel, so as to produce a corresponding downward projection of the mar-

gins and corners of the pad 16, as shown in Figs. I, III and IV. For this purpose, strips 19 and corner-pieces 20 of wedge-shaped cross-section are shown attached to the lower face of the plate 17 at its margins,—which is a less costly construction than to make the plate 17 itself with edges similarly augmented. These pieces 19, 20 may be of hard vulcanized rubber cemented to the plate 17. Any suitable cement or adhesive may be used for attaching the pieces 19, 20 and the pad 16: e. g., ordinary shellac dissolved in alcohol. For this purpose, a rather thick shellac may be applied to both plate 17 and pad 16 (3 coats on the plate, and 1 or 2 on the pad), and the pad then applied to the plate while the last coats of shellac are still fresh and wet. The shellac may then be allowed to set under the weight of the plate 17 resting on the pad 16: i. e., a pressure of about 10 lbs. per square inch.

The facing pad 16 need not necessarily be in a single piece, but may, on the contrary, consist of a number of rectangular pieces 21 25 trimmed down from standard commercial 40 in. x 40 in. sheets 1 in. thick, and arranged edge to edge (Figs. I and II). Preferably, the edges of these smaller sheets 21 are vulcanized together or cemented together with 30 ordinary rubber cement, so as to form one large sheet 16 of the size required for a commercial wet machine, before being applied to the backing plate 17. As shown in Figs. I, III, and IV, the thus built-up rubber pad 35 16 is covered or faced with a single sheet of textile fabric 22, preferably a wool felt about $\frac{1}{2}$ in. or more thick. This covering 22 may be cemented to the pad 16 with ordinary rubber cement.

40 Fiber sheets made in a wet machine with a mold top 10 surfaced as above described do not stick to the mold top, but come away from it spontaneously as it rises, without really lifting from the conveyor wires 15. This is 45 equally true without the felt covering 22,— which, indeed, need only be used to prevent the joints between the individual rubber sheets 21 from marking the fiber sheets formed in the mold. The felt 22 and its attachment by 50 rubber cement to the rubber pad 16 does not materially clog or occlude the pores of the sponge rubber, nor impair its absorptive power.

55 In operation, the 1 in. pad 16 compresses (as shown in heavy dotted lines in Figs. III and IV) to a thickness of about $\frac{5}{8}$ in. when the pulp is squeezed in the mold, so that its pores are flattened shut and remain uncharged with water, which drains away through the 60 screen 13 just as fully as if the pad 16 did not exist. When the pressure of the mold top 10 is released, however, the pad 16 expands and its pores absorb the water from the top of the formed fiber sheet. The edges 65 of the pad 16 pack against the deckle walls

and prevent water from the pulp from working up around the edges of the top 10; and if any water does work up in this manner, the edges of the pad absorb it when the deckle 70 14 is raised, and keep it from dripping on the fiber sheet and wetting its edges. The pad 16 also acts as a cushion to protect the conveyor wires 15 if the top 10 should inadvertently be lowered on the bottom 11 with the mold empty. While the edges and corners 75 of the pad 16 compress and deflect more than its central portion under the same loading, as indicated by the heavy dotted lines in Figs. III and IV, this is compensated for by the wedges 19, 20, so that the resultant fiber sheet is of uniform thickness right out to its 80 very edges.

Having thus described our invention, we claim:

1. In a mold of the character described, 85 for forming sheets from fiber pulp by squeezing out the water, a mold top faced with elastic sponge, whereby sticking of the formed fiber sheet to the top is prevented.

2. In a mold of the character described, for 90 forming sheets from fiber pulp by squeezing out the water, a mold top comprising a metal plate and a facing pad of sponge rubber cemented thereto, whereby sticking of the formed fiber sheet is prevented.

3. In a mold of the character described, for 95 forming sheets from fiber pulp by squeezing out the water, a mold top having a pad of elastic sponge sheets secured thereto, edge to edge, and a sheet of porous fabric secured 100 over said facing, so as to prevent its joints from marking the fiber sheets formed in the mold.

4. In a mold of the character described, for 105 forming sheets from fiber pulp by squeezing out the water, a mold top having a flat bottom surface with swelling edges and corners, and a facing pad of elastic sponge, of substantially uniform thickness over said top, including its edges and corners, whereby a 110 fiber sheet of uniform thickness is produced in the mold, and sticking of the sheet to the mold top is prevented when the mold is opened.

5. In a mold of the character described, for 115 forming sheets from fiber pulp by squeezing out the water, a mold top comprising a flat metal plate, wedges secured thereto along its edges, a facing pad of sponge rubber cemented to said plate and wedges, and a sheet of 120 porous fabric cemented over said pad.

In testimony whereof, we have hereunto signed our names at Trenton, New Jersey, the 10th day of November, 1930.

FRANCIS S. FARLEY.
HUGO FELIX WALTER.
